APPARATUS FOR COOLING AND RECTIFYING MIXED GASES

William Lane De Baufre, Lincoln, Nebr.

Application November 9, 1935, Serial No. 49,075

24 Claims. (Cl. 62—122)

This invention relates to the art of separating mixed gases by cooling and rectification and is particularly useful in the separation of atmospheric air into more or less pure oxygen and nitrogen without the necessity of first removing the water vapor and carbon dioxide therefrom. Atmospheric air contains varying quantities of water vapor depending upon its temperature and relative humidity. It also contains a small percentage of carbon dioxide. In cooling atmospheric air to the temperature of liquefaction, which is necessary before the air can be subjected to rectification, water vapor is condensed out of the mixed gases as liquid water above zero centigrade and frozen out as solid ice (frost) below zero centigrade. Carbon dioxide sublimes out of the air at temperatures below minus 80 centigrade.

Interchangers for cooling compressed atmospheric air have been arranged for defrosting so that it was unnecessary to remove water vapor from the air before cooling the same. But it has been necessary to warm such interchangers to atmospheric temperature at frequent intervals in order to defrost the heat transferring surfaces. Also, it has been proposed to employ recuperators for cooling air to be rectified by means of heat absorbing material previously cooled by products of rectification, ice and carbon dioxide deposited on the surface of the heat absorbing material while cooling air being re-evaporated by the pure dry products of rectification. Such recuperators, however, have many disadvantages; and, in the ordinary arrangement of air separation plants, ice and carbon dioxide would be carried through such recuperators and be deposited in other parts of the plant, such as the engine or turbine for supplying refrigeration thereto, thereby causing difficulties in operation and in maintenance.

The general object of the present invention is to arrange an air separation plant so that the process can be conducted satisfactorily without purifying the air of water vapor or carbon dioxide. Other objects of the invention are:

To supply to the rectifier substantially constant quantities of the atmospheric air or other mixed gases to be rectified and to withdraw therefrom substantially constant quantities of the products of rectification in order that the rectifier will function at its highest effectiveness and the products of rectification will be of substantially constant purity irrespective of variations in resistance to flow of the atmospheric air or other mixed gases through the cooling apparatus.

To provide means for securing any desired

purities of products with high efficiency both by changes in operating conditions and by changes in design proportions.

To obtain one of the products of rectification without contamination by the original mixed gases.

To remove from the cooling apparatus without shutting down the plant, impurities which accumulate over a number of cycles of operation.

To accomplish the preceding objects, an auxiliary cycle is provided for refrigeration purposes and for producing or augmenting the liquid and vapor refluxes required in rectification.

A subsidiary object of the invention is to so arrange this auxiliary refrigeration cycle in combination with the main rectification cycle that the plant may be cooled to operating temperatures by utilizing the mixed gases to be separated. And, in the process of cooling and during normal operation, less volatile constituents will be removed from the fluid circulated in the auxiliary refrigeration cycle, thereby making this fluid suitable for use as the liquid reflux in the main rectification cycle.

The auxiliary refrigeration cycle is so arranged that the apparatus therein may be cooled to operating temperatures without cooling the rectifier in the main rectification cycle.

The foregoing objects together with such additional and subsidiary advantages as may hereinafter appear or are incident to the invention, are realized by the novel method and apparatus described herein and shown in preferred form on the drawings as follows:

Figure 1 shows a schematic arrangement of an air separation plant wherein two sets of recuperators are employed for cooling two measured portions of the air to be separated, the heat absorbing material within the recuperators being cooled by respective measured products of rectification. Figure 2 shows an air separation plant with combined recuperators and interchangers employed as regenerators for cooling a measured portion of the air to be rectified, the products of rectification also being withdrawn in measured quantities. In Fig. 1 and Fig. 2, a single stage rectification column is shown. Figure 3 shows a two-stage rectification column with means for supplying measured quantities of the mixed gases thereto and removing measured quantities of the rectification products therefrom, the mixed gases being cooled by the rectification products in combined recuperators and interchangers as regenerators.

Three different ways of utilizing an auxiliary

refrigeration cycle in combination with the main rectification cycle are shown in these three figures, the auxiliary cycle in all cases contributing to the vapor and liquid refluxes required in the main cycle. In Fig. 3, the auxiliary cycle contributes to the refluxes produced in a final stage of rectification by means of a preliminary stage of rectification. In Fig. 1 and Fig. 2 the vapor and liquid refluxes for a single stage rectification are produced by means of the auxiliary cycle.

Figure 4 shows in detail the arrangement of the combined recuperator and interchanger employed as a regenerator in Fig. 2 and Fig. 3. The means for controlling the operation of the valves through recurring cycles of operations are also shown together with the means for controlling the warming of any one regenerator to room temperature. Figure 5 shows an alternative arrangement of heat absorbing material among the tubes of the combined recuperator and interchanger shown in Fig. 4.

The apparatus shown on the drawings comprises:

(1) Compressor A with positive displacement cylinders B, C, D and E for supplying measured portions of atmospheric air or other mixed gases to the cooling and rectifying apparatus and for withdrawing therefrom measured portions of the products of rectification. This compressor is driven by motor M.

(2) Regenerators F, G, H and F', G', H', Fig. 1, for cooling the measured portions of mixed gases by heat exchange with material which has previously been cooled by the measured products of rectification. In Fig. 2 and Fig. 3, the regenerators F, G and H are combined recuperators and interchangers, the measured portion of mixed gases being cooled partly by direct heat exchange with one of the measured products of rectification.

(3) Rectifier R for rectifying the cooled mixed gases into more or less pure products. In Fig. 3, the two-stage rectifier is made up of final rectifier R₁, preliminary rectifier R₂ and exchanger R₃.

(4) Combined compressor and expander W with positive displacement cylinders Q and S for compressing the gas which is to be cooled and partly liquefied in the auxiliary cycle, and positive displacement cylinder P (or equivalent turbine) for expanding the cooled compressed gas. This unit is driven by motor N.

(5) Interchanger K for cooling the compressed gas from unit W.

(6) Liquefier L for partly liquefying the cooled compressed gas.

(7) Storage tank T for storing the gas to be compressed and cooled in the auxiliary cycle.

(8) Purifier V for removing water vapor and carbon dioxide from the compressed gas to be cooled in the auxiliary cycle.

(9) Main controller X, Fig. 4, for periodically changing the flows of mixed gases and products of rectification through the regenerators.

(10) Auxiliary controller Y for warming each regenerator in turn to room temperature in order to remove therefrom impurities which accumulate over a number of cycles of periodic changes in flow.

Operation of the above listed equipment will be described for separating atmospheric air into more or less pure oxygen and nitrogen, for which the apparatus is specially adapted.

Atmospheric air is supplied through pipe 1 usually at about atmospheric pressure. Measured portions of atmospheric air are withdrawn from

pipe 1 by positive displacements of the pistons within cylinders B and C in Fig. 1 and these measured portions are supplied to the two sets of regenerators (recuperators) F, G, H and F', G', H'. This feature of the present invention is covered in patent application Serial No. 44,616 filed Oct. 11, 1935. In Fig. 2 and Fig. 3, one positive displacement cylinder B only is required to supply a measured quantity of air since the air to be cooled is not divided into two portions.

In all cases, the measured quantity of air to be separated is cooled substantially to the temperature of rectification by measured portions of products of rectification withdrawn by positive displacements of the pistons within cylinders D and E. As indicated in the figures, the pistons within cylinders D and E are driven by cranks on the same shaft as the cranks driving the pistons within cylinders B and C. Consequently, the positive displacements of the means for supplying the portions of air to the separation unit have a constant ratio to the positive displacements of the means for withdrawing products of rectification therefrom. Evidently, for any given pressure of the air within pipe 1, there will be a corresponding pressure of rectification determined by this ratio.

The volume of either portion of air or of either product of rectification will vary with the clearance volume of the compressor cylinder in question. By providing clearance pockets and valves 2, 3, 4 and 5 for opening or closing such pockets to the cylinders, the volume flow for any cylinder may be changed at will. The flow ratio will thereby be changed either for varying the pressure of rectification, for varying the purities of the products of rectification, or for adjusting the portions of air supplied to the cooling effects of the returning products of rectification.

Thus, it is evident that in steady operation, the mass of products removed from the rectifier must equal the mass of mixed gases supplied for rectification. The former mass is equal to the sum of the products of the densities of the components of rectification at approximately the rectification pressure and the respective piston displacements within cylinders D and E as affected by the clearance volumes. The latter mass is equal to the sum of the products of the density of the mixed gases at substantially the pressure in pipe 1 and the piston displacements within cylinders B and C as affected by the clearance volumes of these cylinders. Hence, to every pressure in pipe 1 there is a corresponding rectification pressure determined by the displacements and clearance volumes. Any relative change in displacements or clearance volumes will therefore change the rectification pressure relative to the pressure in pipe 1.

The relative quantities of the products of rectification must evidently correspond to the purities desired, assuming the effectiveness of the rectification column to be sufficient to produce the desired purities of the products. If the quantities of products are withdrawn in any different ratios, the purities will be affected thereby. Positive piston displacements within cylinders D and E enable the correct ratio of products for any desired purities to be attained and maintained by proper design proportions. By varying the clearance volumes, this ratio may be changed with fixed displacement volumes and corresponding changes made in the purities of the products during operation.

As any changes in the quantities of rectification products will vary the cooling effects in the

two sets of regenerators in Fig. 1, corresponding changes will be desirable in the portions of air measured by the positive displacements within cylinders B and C. Changes in the clearance 5 volumes of cylinders B and C will vary the ratio of the two measured portions of mixed gases, thereby enabling the two portions to be adjusted to the cooling effects of the returning rectification products.

10 At low pressures of the air to be rectified relative to the pressure of rectification, as would be the case in the apparatus of Fig. 1 and Fig. 2, clearance pockets may need to be very large for changes desired in the ratio of the products of rectification or of the two portions of the air to be rectified. In such cases, some equivalent means may be employed for changing this ratio, such as mounting the cranks for the air cylinders on a different shaft from that containing the cranks for the products cylinders, and then connecting the two shafts through a speed changing device, such as represented by 50 in Fig. 2 and Fig. 3. But in any case, there is a mechanical connection between the positive displacement devices 15 for maintaining substantially constant the ratio of the two products of rectification withdrawn from the rectifier and the ratio of the mixed gases to the rectification products by driving compressor A by motor M.

20 By positive displacement means for supplying the air to be rectified and positive displacement means for withdrawing the products of rectification, rectifier R may be operated at any desired pressure of rectification, either above or below 25 atmospheric pressure or the pressure within pipe I. By operating below atmospheric pressure, advantage can be taken of the wider spread at lower pressures between compositions of liquid and vapor in phase equilibrium, thereby increasing the 30 effectiveness of any given rectifier.

25 By opening any inlet or outlet pipe to the atmosphere, the pressure within the system will be maintained substantially at atmospheric pressure at that point. In such case, one positive displacement compressor cylinder can be omitted and the apparatus will function in the same manner as previously described with the exception that rectification will be conducted substantially 40 at atmospheric pressure. If an inlet pipe be connected directly to pipe I, rectification will be conducted substantially at the pressure in pipe I.

50 Thus, in Fig. 1, if pipe 6 be open to the atmosphere or connected directly to pipe I (as shown by dotted lines) compressor cylinder C can be omitted. The portion of air drawn directly from the atmosphere or from pipe I, will be determined by the difference between the positive displacements of cylinders B, D and E. In Fig. 2, cylinder B can be omitted and all air drawn in directly from pipe I or the atmosphere through the dotted pipe shown.

55 Also, one of the positive displacement cylinders, for withdrawing a product of rectification can be omitted, this product being discharged directly into the atmosphere. Then, if the air were supplied by positive displacement means, the amount of this product would be maintained substantially constant by positive displacement means for withdrawing the other product of rectification. Thus, 60 in Fig. 3, cylinder D can be omitted for withdrawing the nitrogen product of rectification and this product can be discharged through the dotted pipe shown and maintained constant by the positive displacement means for supplying the air to

be rectified and positive displacement means for withdrawing the oxygen.

Finally, one of the positive displacement compressor cylinders can be replaced by a type of compressor which is not of the positive displacement type, such as a centrifugal type compressor. Rectification will then be carried on at any desired pressure above or below atmospheric pressure as determined by the centrifugal type compressor.

10 In any case, all but one inflowing or outflowing fluid must be supplied or withdrawn by positive displacement means in order to obtain the advantages described.

15 By varying the speed of motor M, the displacements of all cylinders B, C, D and E are varied in proportion. The proper ratio of the two products of rectification is therefore maintained at all capacities of operation of the plant. At the same time, the two portions of the air to be rectified are 20 maintained in proper relation to the two products of rectification with separate sets of regenerators as shown in Fig. 1.

25 The air to be separated flows through pipes 6 and 7 from compressor cylinders C and B respectively to one of regenerators F, G, H and F', G', H'. A product of rectification returns through the remaining regenerators in parallel. By providing three or more regenerators connected in parallel, the returning product of rectification 30 flows through at least two regenerators in parallel while the mixed gases flow through one regenerator. This provides the lower velocity for the returning product and the longer time for re-evaporation of impurities described and claimed in 35 patent application Serial No. 44,616 filed Oct. 11, 1935. This is true for the regenerators shown in Fig. 2 and Fig. 3 as well as in Fig. 1.

40 In Fig. 2 and in Fig. 3, means are shown for warming any one of the regenerators above the freezing temperature of water in order to remove therefrom impurities which have accumulated over a number of cycles of operation. This becomes possible by having three or more regenerators in parallel so that at least one regenerator is available for warming a returning product of rectification and a second regenerator is available for cooling the mixed gases while the third regenerator is being warmed above the freezing temperature of water.

50 Referring to Fig. 2 and Fig. 3, assume valves a, b, c, l, m, s, t and v open and valves e, f, g, h, i, j, n, o, p, q and u closed. Then the air from cylinder 15 flows through pipe 7 and up through regenerator F while the oxygen product of rectification flows through pipe 8 from rectifier R and down through tubes 9 within regenerator F. The air is cooled partly by heat transfer to the returning oxygen product of rectification within tubes 9 and partly by slightly warming heat absorbing material placed around tubes 9 as shown in Fig. 4 and Fig. 5. The material of tubes 9 also stores up some heat. No oxygen returns through the tubes within the remaining regenerators but the nitrogen product of rectification 55 flows from rectifier R through pipe 10 and then flows down through the heat absorbing material surrounding the tubes within regenerators G and H.

60 Any frost and sublimed carbon dioxide which have been deposited upon the surfaces of the tubes within regenerators G and H and of the heat absorbing material surrounding these tubes while air was being cooled, are more or less re-evaporated and absorbed by the nitrogen product 65

of rectification which returns from rectifier R practically free of water vapor and carbon dioxide. The returning nitrogen cools the heat absorbing material surrounding the tubes in these regenerators and also the material of the tubes themselves.

After a period of operation in the above manner, either regenerator G or H may be substituted for regenerator F. For example, by closing valves *l* and *m*, the return flow of nitrogen through regenerator G is shut off. Then, by opening valves *h*, *i* and *j*, flow of air and of returning oxygen is started through regenerator G. Valves *a*, *b* and *c* may then be closed to shut off flows of air and oxygen through regenerator F and valves *e* and *f* opened for flow of returning nitrogen therethrough.

After a number of cycles of operation of each regenerator, first for cooling the air to be rectified and warming the returning oxygen and then for warming returning nitrogen, there is an accumulation of frost and carbon dioxide snow on the surfaces of the heat absorbing material and of the heat transfer tubes. Suppose that it is desired to raise the temperature of regenerator H above the freezing temperature of water in order to re-evaporate all frost and carbon dioxide snow accumulated therein. This may be accomplished by closing valve *t*, opening valve *u* and closing valve *v* in sequence. The nitrogen returning through regenerator F or G will then flow up through regenerator H.

Entering at approximately room temperature, the nitrogen will warm the heat absorbing material within regenerator H above the freezing temperature of water. Any resulting water may be removed through drain 18 shown in Fig. 4. The carbon dioxide will be gasified and leave with the outflowing nitrogen.

An upward flow of the warm nitrogen through the regenerator is desirable in order that water from melted ice will run down to warmer regions within the regenerator. An upward flow of the air being cooled is also desirable in order that condensed vapor will run down to warmer regions. Downward flows of returning cold oxygen and cold nitrogen are then necessary in order for these fluids to be in counterflow relation to the air cooled.

The preferred construction of such a combined recuperator and interchanger is shown in Fig. 4. Tubes 9 extend from upper fixed tube sheet 11 to lower floating head 12. The returning oxygen enters through pipe 8 and leaves through pipe 13 which passes through the packed stuffing box shown. Tubes 9 are more widely spaced than customary in interchangers for air liquefaction and separation plants. The spaces between tubes 9 contain heat absorbing material.

As shown in the left half section, such material may consist of rods or tubes in layers with the rods or tubes in each succeeding layer crossing the rods or tubes in the preceding layer. In order to cause a flow of the air to be cooled across tubes 9, baffles 14 may be inserted at intervals. In the right half section, the heat absorbing material is shown in the form of corrugated strips (or cylinders) 15. In Fig. 5, the corrugations are shown in another position with plain circular sheets 16 placed between tubes 9 and corrugated circular sheets 17. In either case, the corrugated sheets may be perforated to permit cross flow of air and nitrogen, and baffles such as 14 may be employed to induce such cross flow.

The floating head construction shown permits

relative expansion and contraction of tubes and shell, both during the small temperature changes of the normal cycle of operations and during the greater temperature changes in warming for defrosting and cooling again to normal operating temperatures. By having the shell of greater inside diameter than the outside diameter of the floating head, the heat transfer surface and the heat absorbing material may be readily removed from the interchanger shell. This is accomplished by disconnecting at flanges 47, 48 and 51. The plate closing the lower end of the shell and holding the stuffing box may then be lifted through the shell with the heat transfer surface and the heat absorbing material. The inside 15 flanged connection at 48 makes this possible.

The construction described and shown facilitates manufacture and renewal of tubes and heat absorbing material after the plant is assembled. The construction is made possible by the heat absorbing material surrounding the tubes. Without such material in the spaces between the tubes, heat absorption by the tubes would be so poor as to render the construction impractical because this construction could not be employed with 25 closely spaced tubes.

Figure 4 also shows a means for operating all valves from a central control point, both for shifting the flows through the normal cycle of operations and for warming each regenerator 30 above the melting temperature of ice. The valves are designated by the same letters *a*, *b*, *c*, *e*, *f*, *g* and *v* as in Fig. 2 and Fig. 3. Each of these valves may be closed by admitting an operating fluid under pressure to the cylinder containing 35 the piston attached to the valve stem. By releasing the pressure, the valves are opened by the springs shown assisted by any excess of fluid pressure under the valve disk relative to the fluid pressure above the main disk. Controllers X and Y admit the operating fluid to the several cylinders and release it therefrom.

Operating fluid is supplied under pressure through tube 19 to controllers X and Y and is exhausted through tube 20. By turning the 45 handles indicated, pressure and exhaust tubes 19 and 20 are brought into communication with the operating tubing running to the several cylinders. The several valves are shown in the positions for warm nitrogen returning from one or more other 50 regenerators to flow through pipe 21 and valve *e* up through the shell of the regenerator shown, out through valve *g* and thence through pipe 49, valve *v* being closed. Valve *f* is also closed to prevent flow of nitrogen in through valve 4, down 55 through the regenerator and out through valve *e*. Valves *a* and *b* are closed to prevent flow of air therethrough. Valve *c* is closed to prevent flow of oxygen through this regenerator while being warmed above the melting temperature of ice.

Controllers X and Y are so arranged that valve *g* can be opened only when nitrogen is flowing through the regenerator and cannot be opened when air is flowing therethrough. When air is flowing through this regenerator, a movement of 65 the handle of controller Y cannot open valve *f*. Valve *v* can be closed only when valves *f* and *g* are moved to the positions shown for this or one of the other regenerators. This interlocking is accomplished by arranging the tubing as shown 70 for supply and exhaust of the operating fluid.

Thus, in the position shown for main controller X, tubing 22 is connected to pressure tube 19, thereby closing valves *a*, *b* and *c*. In any other position of the operating handle, tubing 22 is con- 75

nected to exhaust tube 20, thereby opening valves a, b and c. These three valves thus always operate together, air and oxygen flowing through the regenerator at the same time.

5 In the position shown for main controller X, tubing 23 is connected to exhaust tube 20, thereby permitting valve e to open. Valve e is therefore always open when valves a, b and c are closed, and vice versa.

10 From valve f, tubing 24 is connected to auxiliary controller Y instead of main controller X. Normally, tubing 24 is connected to tubing 23 within controller Y so that valve f opens and closes simultaneously with valve e by movement 15 of controller X. But with the handle of auxiliary controller Y in the position shown, tubing 24 is connected with pressure tube 19, thereby closing valve f. By moving the handle on controller Y, tubing 23 can be connected either with pressure 20 tube 19 or with operating tubing 23. Therefore, valve f cannot be opened by controller Y when closed by controller X but can be closed by controller Y when opened by controller X.

For valve g, tubing 25 is connected to auxiliary controller Y and in the position shown is connected to tubing 23 which is connected to exhaust tube 20 within main controller X. In any other position of auxiliary controller Y, tubing 25 is connected to pressure tube 19. Therefore, 30 valve g can be opened by controller Y only when tubing 23 is connected by controller X to exhaust tube 20; that is, only when valve e is open. When valve e is held closed by tubing 23 being connected to pressure tube 19 within main controller 35 X, valve g cannot be opened by moving auxiliary controller Y to any position.

For valve v, tubing 26 in the position shown of auxiliary controller Y is connected to tubing 22 which is connected within main controller X to pressure tube 19. In any other position of auxiliary controller Y, tubing 26 is connected to exhaust tube 20. Tubing 26 can thus be connected to pressure fluid only through tubing 22. Hence, valve v can be closed only when tubing 22 is connected within main controller X to pressure tube 45 19 and valves a, b and c are therefore closed.

The arrangements of regenerators and operating valves as previously described may be used with single-stage rectification as shown in Fig. 1 50 and Fig. 2 or with two-stage rectification as shown in Fig. 3 and in patent application Serial No. 44,616 filed Oct. 11, 1935.

Referring to Fig. 1 and Fig. 2, rectifier R is a single-stage column with a vaporizer at the bottom for vaporizing the more or less pure liquid oxygen leaving the lowest plate within the column. This liquid oxygen flows through pipe 27 to the space surrounding tubes 28 in the vaporizer. Nearly pure nitrogen vapor is condensed 55 within tubes 28 in vaporizing the liquid oxygen. The resulting oxygen vapor leaves through pipe 29, part returning to the column as a reflux vapor and part returning through pipe 8 to regenerators F, G, H. The condensed nitrogen leaves through pipe 30 and is throttled through valve w onto the top plate within column R where it serves as a reflux liquid in rectifying air entering the column through pipe 31.

The nitrogen which condenses within tubes 28 70 in Fig. 1 and in Fig. 2, is supplied by means of an auxiliary refrigeration cycle. In Fig. 3, the nitrogen comes largely from a preliminary rectification of the air to be separated and is augmented by nitrogen from an auxiliary refrigeration cycle.

75 Referring to Fig. 3, the two-stage rectification

column is divided into a final rectifier R₁, a preliminary rectifier R₂ and an exchanger R₃. Air to be separated enters preliminary rectifier R₂ through pipe 31 and is there rectified into a nearly pure nitrogen vapor and an oxygen-rich liquid. The oxygen-rich liquid flows through pipe 44 and is throttled by valve y onto an intermediate plate in final rectifier R₁. The nearly pure nitrogen vapor is partly condensed within the tubes of preliminary rectifier R₂ to form a liquid reflux for the preliminary rectifier. The remaining nitrogen vapor flows through pipe 45 and is liquefied within tubes 28 of exchanger R₃, the resulting liquid nitrogen flowing through pipe 30 and being throttled through valve w to form a liquid reflux within final rectifier R₁. Oxygen vapor enters final rectifier R₁ through pipe 29 and forms the vapor reflux therein. Liquid oxygen not vaporized within preliminary rectifier R₂ flows through valve z into exchanger R₃ where the vaporization is completed. Oxygen vapor returns through pipe 8 to regenerators F, G, H.

With two-stage rectification, the air cooled within regenerators F, H, G, is discharged into the preliminary stage under say 50 lb. pressure as compared with being discharged into the rectifier at about atmospheric pressure with single-stage rectification. The combined recuperator and interchanger has even greater advantages 30 in reducing contamination of one product of rectification with two-stage rectification shown in Fig. 3 than with single-stage rectification shown in Fig. 2.

In all cases, nitrogen for the auxiliary refrigeration cycle is withdrawn from the rectifier through pipe 32 connected to nitrogen return pipe 10 (or to the rectifier top). In flowing through liquefier L and interchanger K, this cold nitrogen is warmed approximately to room temperature and then flows through pipe 33 to compressor cylinder Q. Here the nitrogen is compressed to about 50 lb. gauge and discharged through pipe 34. In returning through interchanger K and liquefier L, the compressed nitrogen is cooled in K and partly liquefied in L by heat exchange with the cold nitrogen withdrawn from rectifier R. The partly liquefied nitrogen flows through pipe 35 to the vaporizer in Fig. 1 and Fig. 2 or to the preliminary rectifier in Fig. 3. 50 In all cases, the nitrogen vapor is liquefied within tubes 28 by vaporizing liquid oxygen surrounding these tubes, thereby producing vapor reflux for rectification of the air to be separated. Also, resulting liquid nitrogen flows through pipe 30 55 and is throttled through valve w into the rectifier as a liquid reflux for rectifying the air to be separated.

The pressure to which the nitrogen of the auxiliary refrigeration cycle is compressed within cylinder Q, is substantially equal to the pressure necessary to liquefy the nitrogen by heat transfer to the oxygen being vaporized at the pressure of rectification. The compression pressure exceeds this liquefaction pressure only by the frictional resistance to flow through interchanger K and liquefier L. There is thus avoided the thermodynamic loss due to a large drop in pressure caused by throttling partly liquefied nitrogen from liquefier L to some lower pressure before utilizing it for producing the vapor reflux in rectifying the air to be separated. In Fig. 1 and Fig. 2, vapor and liquid refluxes are produced by utilizing the nitrogen of the auxiliary refrigeration cycle. In Fig. 3, vapor and liquid refluxes pro- 75

duced in this way augment refluxes produced in the final stage of rectification by means of the preliminary stage of rectification.

In Fig. 2, a fraction of the compressed and cooled nitrogen saturated vapor remaining after liquefying some of it within tubes 28, is withdrawn in gaseous form through pipe 40, flows up through tubes within liquefier L where it is superheated by heat exchange with nitrogen being cooled and liquefied therein. The superheated nitrogen gas flows thence through pipe 46 to expander P. In expanding with performance of external work, the superheated nitrogen is cooled. The cooled expanded nitrogen is then exhausted through pipe 41 into nitrogen return pipe 10 to regenerators F, G and H beyond the point of connection of pipe 32 to pipe 10. It is desirable to superheat the saturated nitrogen vapor withdrawn from the vaporizer before expanding this vapor in order to obtain a more efficient operation of expander P. The expander P is shown as a reciprocating engine with positive displacement of the piston up to the point of cut-off. In many ways, however, a turbine with fixed orifice for flow of nitrogen therethrough would have similar characteristics.

In Fig. 1 and Fig. 3, a fraction of the nitrogen compressed by compressor cylinder Q is withdrawn from pipe 34 through pipe 36 by compressor cylinder S. This fraction is further compressed to a higher pressure and discharged through pipe 37 to interchanger K. Within interchanger K, the further compressed nitrogen is cooled to a low temperature. It does not reach the saturated vapor temperature but is discharged in a superheated condition through pipe 38 to expander P.

In Fig. 1, the further compressed and cooled nitrogen is expanded in expander P and is then discharged through pipe 39 into the vaporizer of the rectification column. Here the expanded nitrogen vapor is liquefied by heat transfer to the liquid product of rectification, thereby augmenting the vapor reflux produced by liquefying the nitrogen vapor compressed just to the pressure necessary for liquefaction. The resulting nitrogen liquids commingle and are throttled through valve w into the rectification column as the liquid reflux. Liquefied expanded vapor thus augments the liquid reflux for rectification of the air to be separated.

In Fig. 3, the further compressed and cooled nitrogen is expanded in expander P to the pressure of the final stage of rectification. At this pressure, the expanded nitrogen, further cooled by performance of external work, is discharged through pipe 41 into pipe 10 for nitrogen returning to regenerators F, G and H, at a point beyond the connection of pipe 32 to pipe 10.

In all cases, T is a storage reservoir for nitrogen on the suction side of the compressor and v represents purifiers for removing carbon dioxide, water vapor and oil from the compressed nitrogen gas.

In starting the plant, particularly for the first time or in the absence of storage tank T, the mixed gases to be separated may be admitted to the rectifier and be drawn therefrom into the refrigeration cycle through pipe 32 by starting motor N driving compressor Q. In case of an air separation plant, atmospheric air may be admitted to the refrigeration cycle at the suction of compressor Q so that it will pass through purifiers v before being cooled, thereby avoiding any accumulation

of carbon dioxide and frost in the refrigeration cycle at starting.

In all cases, interchanger K and liquefier L only are cooled to operating temperatures without cooling rectifier R. In Fig. 1, by-pass valve x is provided for opening at starting so that the expanded gas from expander P passes directly to liquefier L and thus returns through liquefier L and interchanger K without entering rectifier R. In Fig. 2 and Fig. 3, the expanded gas flows from pipe 41 to pipe 32 without flowing through rectifier R, so that no by-pass valve is necessary at starting to cool down the interchanger and liquefier in the auxiliary refrigeration cycle without cooling down the rectifier. This is accomplished by connecting both discharge pipe 41 and inlet pipe 32 to return pipe 10 from rectifier R to regenerators F, G, H.

While cooling down, valves w and y are closed so that all of the gas compressed by the pistons in cylinders Q and S is expanded in expander P. Clearance pockets are provided on cylinders Q and S with valves 42 and 43 in order that the amount of gas compressed may be reduced while cooling down so that excessive compression pressures may be avoided, particularly while the temperature at the inlet to expander P is above normal operating temperature.

When interchanger K and liquefier L have reached approximately operating temperatures, part of the compressed gas will be liquefied within liquefier L. The resulting liquid will drain through pipe 35 into the bottom of the vaporizer on rectifier R in Fig. 1 and Fig. 2. In Fig. 3, the trays within preliminary rectifier R₂ will fill with liquid draining through pipe 35 before any liquid accumulates in the pot at the bottom. By opening valve w slightly, liquefied gas may be discharged into the top of the rectifying column to fill the trays therein. In the arrangement shown in Fig. 1, valve x may be partly closed to raise the pressure in order to force the liquefied gas through valve w.

While the gaseous mixture is being liquefied within liquefier L, the liquid formed is more or less in phase equilibrium with the remaining vapor. That is, the liquid formed will contain a higher percentage of the less volatile constituent than the remaining vapor. Consequently, the remaining gas becomes richer in the more volatile constituent of the original gaseous mixture. By the time normal amounts of liquid accumulate within the rectifier, as shown by the level of the liquid surrounding tubes 28, the gas remaining in the refrigeration cycle will become very rich in the more volatile constituent of the mixed gases to be separated. Valve x is then closed.

Compressor A is now started to supply in measured portions or quantity, atmospheric air or other gaseous mixture to be cooled and rectified. Measured quantities of the rectification products are withdrawn at the same time.

The method of starting described will result in the rectification products having purities approaching those desired as soon as normal flows are established. Any deficiencies will soon be remedied by the method employed of drawing into the refrigeration cycle a portion of the volatile product of rectification through pipe 32 to replace the gas left therein by the starting operation. The volatile product of rectification approaches phase equilibrium with liquefied gas from the refrigeration cycle injected into the rectifier as a liquid reflux. The volatile product of rectification is therefore richer in the more volatile constituent of the mixed gases than the gas in the

refrigeration cycle. The gas in the refrigeration cycle therefore becomes progressively richer in the volatile constituent of the mixed gases rectified until the volatile product of rectification reaches the purity for which the apparatus is proportioned. The less volatile product of rectification will also reach the purity corresponding to the proportions of the rectifier and the auxiliary apparatus.

10 Exhaust pipe 41 from expander P in Fig. 2 and Fig. 3 is connected to pipe 18 from rectifier R to regenerators F, G, H at a point farther from rectifier R than the point of connection to inlet pipe 32 to the refrigeration cycle. This is done so that 15 expanded gas will not be returned through the refrigeration cycle but will be replaced by a fresh portion of the more volatile product of rectification.

During normal operation, valve *w* is regulated 20 to maintain a nearly constant liquid level in the pot of the vaporizer in Fig. 1, and Fig. 2. In Fig. 3, valves *w* and *y* are regulated to maintain constant liquid levels in the pots of exchanger *R*₃ and preliminary rectifier *R*₂. In all cases, the 25 liquid level surrounding tubes 28 is self adjusting if proper design proportions are employed.

Thus, this liquid level determines the wetted surface of tubes 28 which establishes the temperature difference necessary to condense nearly 30 pure nitrogen vapor within tubes 28 by vaporizing nearly pure oxygen liquid outside these tubes. For any given temperature difference, there is a 35 pressure of condensing nitrogen vapor corresponding to the rectification pressure at which the oxygen liquid is vaporized. In Fig. 2, this condensing nitrogen pressure is substantially the initial pressure to expander P. The external work of expander P and the refrigeration furnished thereby to balance heat leak and other 40 thermodynamic losses in the whole process, is a function of the initial pressure. The system will settle down to a liquid level surrounding tubes 28 at which the refrigeration furnished is just equal to that required. Should insufficient 45 refrigeration be supplied, the liquid level will drop until the rise in the pressure of condensation results in increased refrigeration sufficient to balance the requirements. Should the supply of refrigeration be in excess of the requirements, the 50 liquid level will rise until a new balance is reached at a lower initial pressure to expander P.

In Fig. 1 and Fig. 3, the same automatic balancing of refrigeration supplied to that required, is obtained by compressor cylinder S withdrawing 55 a measured quantity of gas from the discharge pipe of compressor cylinder Q substantially at the pressure of condensation of nitrogen within tubes 28. Should this pressure rise, a greater mass of gas would be withdrawn by cylinder S and supplied to expander P. The initial pressure of expansion would therefore rise and more refrigeration be furnished until a balance is reached between supply and demand.

60 During normal operation of any one of the plants shown, main controller *x*, Fig. 4, is moved periodically to change the flows through regenerators F, G, H. This controller might be driven at a slow constant speed by an electric motor. By this means, the valves are operated as previously described to cool two or more regenerators by a rectification product while a single regenerator is being warmed slightly by air or other mixed gases to be rectified. At intervals, one of the regenerators through which a rectification

product returns, is substituted for the regenerator cooling the mixed gases.

At longer intervals after a number of cycles of such operation, each regenerator is in turn warmed above zero centigrade by operating auxiliary controller Y in order to remove frost and carbon dioxide accumulated therein.

During normal operation, the correct proportions of rectification products are continuously withdrawn from the rectifier by positive displacement compressor A slightly affected by variations in pressure drops of said rectification products through the regenerators but irrespective of variations in pressure drops of the mixed gases rectified. Correct proportioning will likewise be maintained between products withdrawn from and portions of mixed gases supplied to the two sets of regenerators in Fig. 1. Adjustments in the ratio of the rectification products or of the portions of mixed gases may be made during 20 operation, however, by means of valves 2, 3, 4 and 5 controlling clearance pockets in the several cylinders or by some equivalent means such as the speed changing device shown as at 50 in Fig. 2 and Fig. 3.

I claim:

1. Apparatus for cooling and rectifying mixed gases including regenerators for cooling the mixed gases and for warming the products of rectification, positive displacement means driven in synchronism for supplying said mixed gases and for withdrawing said products of rectification in measured quantities except one portion of the mixed gases or one product of rectification, and means for maintaining such portion or product 35 at nearly constant pressure whereby the rectification pressure remains substantially at said constant pressure.

2. Apparatus for cooling and rectifying mixed gases including positive displacement means 40 driven in synchronism for supplying said mixed gases and for withdrawing rectification products, regenerators for cooling the mixed gases supplied and warming the rectification products withdrawn, a rectifier for rectifying the cooled mixed 45 gases into a vapor product and a liquid product, means for withdrawing a portion of said vapor product at the temperature of rectification, means for warming the portion withdrawn and for cooling and partly liquefying said portion after compressing it to a higher pressure, a compressor for compressing said portion, a vaporizer for vaporizing the liquid product of rectification and liquefying the cooled compressed portion of said vapor product, means for utilizing the liquefied portion 55 of said vapor product as a liquid reflux in said rectifier, and an expander for expanding with performance of external work a fraction of the portion of said vapor product withdrawn whereby refrigeration is supplied to said rectifier to balance 60 heat leak and other thermodynamic losses.

3. Apparatus for cooling and rectifying mixed gases including positive displacement means driven in synchronism for supplying said mixed gases and for withdrawing rectification products, 65 regenerators for cooling the mixed gases supplied and for warming the rectification products withdrawn, a preliminary rectifier for rectifying the cooled mixed gases into a vapor component and a liquid component, a final rectifier for rectifying 70 said liquid component into a vapor product and a liquid product, heat transfer means for vaporizing said liquid product and liquefying said vapor component, means for utilizing part of the vaporized liquid as a vapor reflux in the final rectifier, 75

- means for utilizing liquefied component as a liquid reflux in said final rectifier, means for withdrawing at the temperature of rectification a portion of the vapor product from said final rectifier, 5 means for warming the portion withdrawn and cooling and partly liquefying said portion after compressing it, a compressor for compressing said portion to the pressure within said preliminary rectifier, means for introducing the partly liquefied portion into said preliminary rectifier whereby the vapor and liquid refluxes are augmented in said final rectifier, and an expander for expanding with performance of external work a fraction of the portion of said vapor product withdrawn whereby refrigeration is supplied to said rectifiers to balance heat leak and other thermodynamic losses.
4. Apparatus for rectifying mixed gases including a rectifier, means for withdrawing therefrom a portion of the more volatile product of rectification at the temperature of rectification, a liquefier and interchanger for warming said portion and recooling and partly liquefying said portion after compressing it, means for compressing said portion, means for expanding a fraction of said portion with performance of external work to furnish refrigeration to said rectifier, and means for cooling said liquefier and said interchanger to operating temperatures without cooling said rectifier.
5. Apparatus for rectifying mixed gases including a rectifier, means for withdrawing therefrom a portion of the more volatile product of rectification at the temperature of rectification, a liquefier and interchanger for warming said portion and for recooling and partly liquefying said portion after compressing it, a compressor for compressing said portion, a vaporizer for liquefying said portion in producing vapor reflux within said rectifier, an expander for expanding a fraction of said portion with performance of external work and means for withdrawing said fraction from said vaporizer.
6. Apparatus for rectifying mixed gases including a rectifier, means for withdrawing a portion of the more volatile product of rectification therefrom, a liquefier and interchanger for warming said portion to room temperature, means for compressing said portion to the pressure at which it is liquefied in vaporizing the less volatile product of rectification, means for further compressing a fraction of said portion, means for passing said fraction through said interchanger whereby said fraction is cooled, an expander for expanding the cooled fraction with performance of external work, means for passing the remainder of said portion through said interchanger and said liquefier whereby the remainder is cooled and partly liquefied, and a vaporizer for vaporizing the less volatile product of rectification by liquefying said remainder.
7. Apparatus for rectifying mixed gases as in claim 6 including means for discharging the expanded fraction of the more volatile product of rectification into said vaporizer whereby said expanded fraction is liquefied in vaporizing the less volatile product of rectification.
8. Apparatus for rectifying mixed gases as in claim 6 including means for commingling the expanded fraction of the more volatile product of rectification with the more volatile product of rectification after withdrawing a portion for warming in said liquefier and said interchanger.
9. Apparatus for rectifying mixed gases as in claim 5 including means for passing said fraction
- through said liquefier whereby said fraction is superheated before being expanded.
10. Apparatus for rectifying mixed gases including a rectifier, an outlet pipe for discharging the more volatile product of rectification therefrom, a refrigeration cycle for furnishing refrigeration to said rectifier, means for withdrawing a portion of the more volatile product of rectification from said rectifier, and for utilizing said portion as the refrigerant in said refrigeration cycle, 10 and means for discharging the refrigerant from said refrigeration cycle into said outlet pipe beyond the point of withdrawal of said portion whereby a fresh portion of the more volatile product of rectification is continuously withdrawn to 15 serve as refrigerant in the refrigeration cycle.
11. Apparatus for cooling and rectifying mixed gases including multiple regenerators which are alternately cooled by a product of rectification and warmed by said mixed gases flowing through 20 the same spaces within said regenerators, and means for warming one of said regenerators above the freezing temperature of water while the remaining regenerators are being alternately cooled and warmed, whereby frost and carbon dioxide 25 accumulated within said regenerator during a number of cycles of cooling and warming are vaporized and removed therefrom without interrupting cooling and rectifying of the mixed gases.
12. Apparatus for cooling and rectifying mixed 30 gases including multiple regenerators which are alternately cooled by a product of rectification and warmed by said mixed gases flowing through the same spaces within said regenerators, a main control mechanism for alternating the flows of 35 said product and said mixed gases through said regenerators in sequence, and an auxiliary control mechanism for warming one of said regenerators above the freezing temperature of water for vaporizing frost and carbon dioxide accumulated 40 therein without interrupting cooling and rectifying of the mixed gases.
13. Apparatus for cooling and rectifying mixed 45 gases as in claim 12 wherein the auxiliary control mechanism is interlocked with the main control mechanism whereby one of said regenerators can be warmed above the freezing temperature of water by means of the auxiliary control mechanism only when the main control mechanism is set for flow of said product of rectification through 50 said regenerator, and the auxiliary control mechanism cannot interrupt the flow of said mixed gases through said regenerator when the main control mechanism is set for such flow.
14. In apparatus for cooling and rectifying 55 mixed gases, a combined interchanger and recuperator for cooling the mixed gases by heat transfer through heat transfer surface to one product of rectification and by heat transfer to heat absorbing material previously cooled by another 60 product of rectification, including a shell, a fixed head and tube sheet at one end of said shell, a floating head and tube sheet at the other end of said shell, tubes extending between the two tube sheets, heat absorbing material between said 65 tubes, and baffles between said tubes and within said heat absorbing material whereby the mixed gases are caused to flow across said tubes and among said heat absorbing material.
15. A combined interchanger and recuperator 70 as in claim 14 wherein said tubes are arranged in circular rows and said heat absorbing material comprises circular sheets of corrugated material.
16. Apparatus for cooling and rectifying mixed 75 gases including regenerators for cooling the mixed

- gases and for warming the products of rectification, and positive displacement means driven in synchronism for withdrawing said products of rectification in measured quantities, whereby the 5 quantities of said products of rectification are maintained in substantially the same ratio irrespective of the operating capacity of the apparatus.
17. Apparatus for cooling and rectifying mixed 10 gases including regenerators for cooling the mixed gases and for warming the products of rectification and positive displacement means driven in synchronism for supplying said mixed gases and for withdrawing said products of rectification in measured quantities, whereby the 15 quantities, of said mixed gases and said products of rectification are maintained in substantially the same proportion irrespective of the operating capacity of the apparatus and the frictional resistances to flow of said mixed gases through said 20 regenerators.
18. Apparatus for cooling and rectifying mixed 25 gases including separate regenerators for cooling separate portions of said mixed gases by warming the respective rectification products, and positive displacement means driven in synchronism for supplying said separate portions to said separate regenerators and for withdrawing therefrom said respective rectification products, whereby 30 the separate portions of said mixed gases are proportioned to the cooling effects of the respective rectification products irrespective of the operating capacity and the frictional resistances to flow of said separate portions through said 35 separate regenerators.
19. Apparatus for cooling and rectifying mixed 40 gases including a rectifier, a refrigeration cycle comprising a compressor for compressing a refrigerant, an expander for expanding said refrigerant with performance of external work, an interchanger for warming said refrigerant and for recooling the refrigerant after being compressed, and a liquefier for warming said refrigerant and liquefying a fraction of the compressed refrigerant, means for returning expanded refrigerant to the liquefier and interchanger without passing it 45 through the rectifier whereby the interchanger and liquefier can be cooled to operating temperatures without cooling the rectifier.
20. In apparatus for cooling and rectifying 50 mixed gases, a rectifier including a vaporizer for vaporizing the liquid product of rectification, a refrigeration cycle for supplying refrigeration to balance heat leak and other thermodynamic losses 55 in said rectifier including an expander for ex-
- panding a refrigerant and means for introducing it into said vaporizer where said refrigerant is liquefied in vaporizing the liquid product of refrigeration, and a by-pass for said vaporizer with valve therein whereby the expanded fluid may be 5 returned to said refrigeration cycle without flowing through said vaporizer by opening said valve.
21. Apparatus for rectifying mixed gases including a rectifier, a refrigeration cycle for furnishing refrigeration to said rectifier by expanding a refrigerant from an initial pressure, a vaporizer for vaporizing liquid from said rectifier and liquefying refrigerant from said refrigeration cycle, a positive displacement compressor for compressing said refrigerant from the pressure of 15 liquefaction in said vaporizer to said initial pressure in the refrigeration cycle, whereby the refrigeration requirements of said rectifier are automatically balanced by the refrigeration supplied by said refrigeration cycle. 20
22. In apparatus for cooling and rectifying mixed gases, a rectifier including a vaporizer for vaporizing the liquid product of rectification, a refrigeration cycle for supplying refrigeration to balance heat leak and other thermodynamic losses 25 in said rectifier, an expander for expanding the refrigerant in said refrigeration cycle, a compressor for compressing the refrigerant to a pressure at which it will liquefy in said vaporizer by vaporizing the liquid product of rectification, a 30 second compressor for compressing said refrigerant to a pressure from which expansion in said expander will supply said refrigeration, and means for operating said expander and said compressors in synchronism. 35
23. In apparatus for cooling and rectifying mixed gases as in claim 22, means for reducing the capacity of said compressors relative to said expander whereby an excessive compression pressure is avoided at starting. 40
24. In apparatus for cooling and rectifying mixed gases, a combined interchanger and recuperator for cooling the mixed gases by heat transfer through heat transfer surface to one product of rectification and by heat transfer to heat absorbing material previously cooled by another product of rectification, including a shell, a fixed head and tube sheet at one end of said shell, a floating head and tube sheet at the other end of said shell, tubes extending between the two tube 45 sheets arranged in circular rows, and heat absorbing material between said tubes comprising sheets of corrugated material. 50

WILLIAM LANE DE BAUFRE. 55
